UNITED STATES PATENT OFFICE.

FRANKLIN R. WHITE, OF WATERBURY, CONNECTICUT, ASSIGNOR TO THE PATENT
BUTTON COMPANY, OF WATERBURY, CONNECTICUT, A CORPORATION OF CON-
NECTICUT.

BUTTON.

Application filed April 21, 1921. Serial No. 463,183.

To all whom it may concern:

Be it known that I, FRANKLIN R. WHITE, a citizen of the United States, and a resident of Waterbury, in the county of New Haven 5 and State of Connecticut, have made and invented certain new and useful Improvements in Buttons, of which the following is a specification.

My invention relates to buttons and particularly to that style or class thereof where- 10 in the fastener is formed as a part of or permanently secured to the head of the button.

An object of the present invention is to 15 provide a button composed of a head and fastener which may be easily and quickly secured to fabric or other material either by hand or by the action of an automatic button attaching machine.

20 A further object is to provide an article of the above-mentioned class which may be securely attached to fabric or other material and without the use or employment of accessory parts, the prongs of the fastener being adapted to curl or bend upon the fabric after having pierced the same and thus securely attach and anchor the head of the button to the material.

25 A further object is to provide a button formed with a head and fastener which can be economically manufactured, is simple in construction, embodies but few parts which may be readily assembled together for the formation of the finished article, and having once been attached to fabric or other material will remain securely anchored thereto and will present a neat, pleasing and finished appearance in use.

30 A further object is to provide a button 40 having a head and a staple fastener secured thereto and in such manner that the button may be secured to cloth or other material by the use of an automatic button attaching machine, the parts being so constructed 45 as to prevent danger or likelihood of the collapsing of the button or loosening of the pronged fastener during the attachment of the button to cloth or other fabric.

With the foregoing and other objects in 50 view, which will appear as the description proceeds, my invention resides in the novel button described and in the combination and arrangement of parts and in the details of construction hereinafter described and

claimed, the preferred embodiment of my 55 invention being disclosed in the accompanying drawing, wherein:

Figure 1 is a view in vertical longitudinal section of a button having the character- 60

istic features of my invention;

Figure 2 is a similar view showing the 65 button securely anchored and attached to fabric or other material;

Figure 3 is a similar view of a somewhat modified form of button, a suitable disc 70 being located above and supporting the base of the pronged fastener or staple;

Figure 4 is a view in vertical longitudinal section of a similar button, the disc being replaced by a filler or anvil extending 75 between the cap of the button and the base of the fastener;

Figure 5 is a top plan view of the button disclosed in Figure 4, portions of the cap being broken away;

Figure 6 is a view in vertical longitudinal section of my improved button, the head being of the open top type;

Figure 7 is a similar view of an open top type button and having a disc located above 80 the base of the fastener and holding the same in place, the head of the button being formed in one piece;

Figure 8 is a view in vertical longitudinal section of a button having a two-piece open 85 top head and provided with a fastener which is anchored in place, similar to the button disclosed in Figures 1 and 6;

Figure 9 is a view in vertical longitudinal section of a button with a two-piece open 90 top head and having a staple or pronged fastener secured or anchored to the body of the button and so held by a suitable disc, similar to the construction illustrated in Figures 3 and 7;

Figure 10 is a view in longitudinal section showing a two-piece closed top button wherein the staple is held in the hub of the button by friction prior to the assembling of the filler therein; and

Figure 11 is a view in vertical longitudinal section showing a button wherein the base of the button is provided with an opening for the passage of the prongs of the staple therethrough so as to prevent the 105 burring of the base.

Referring to the several views, wherein similar reference numerals designate cor-

responding parts throughout, my improved button is composed of a head or body portion A and a pronged fastener B. The head of the button disclosed in Figures 1, 2, 3, 4 of the drawings, is provided with a cap 10 and is of the type known as the closed-top button, the cap being securely fastened to the body portion 11, which latter terminates at its lower end in the hub 12.

10 Prior to the securement of the cap 10 in place, the prongs 13 of the fastener are forcibly driven through the imperforate base 14 of the hub of the button, so as to bring the base 15 of the fastener into contact with and resting upon the base 14 of the hub and in which position it is firmly and securely locked and anchored by the inward crimping or swedging of the body 11 of the button to thereby form the inwardly 20 extending rim or ledge 16. The fastener is thus permanently anchored to the button head and the protruding prongs may be driven through the fabric C or other material and coiled thereupon, as illustrated in 25 Figure 2, thus securely anchoring and attaching the button to the fabric or other material.

The modified form of button illustrated in Figure 3 is similar to the button above described, with the exception that a disc or blank 17 is provided and extends above, so as to contact with, the base 15 of the pronged fastener B. Thus should the base 15 of the pronged fastener vary in size or 35 be imperfect in structure, the disc 17 will retain the fastener properly and securely in place, it being a comparatively simple matter to hold the disc or blank 17 rigidly to dimension and maintain each disc perfect, although manufactured under the conditions 40 of quantity production.

A further feature resides in the slight enlargement of the hub 12', thus materially strengthening the entire button and rendering it more capable of withstanding the crushing strains of the button attaching machine. The hub 12' of the button is provided with the inwardly extending ledge 16' which holds and anchors both the blank 17 and the fastener B in place.

The button disclosed in Figure 4 is also formed with a head D and fastener B and is further provided with what I term a filler or anvil 18, the same extending between the 55 lower surface of the cap 10' of the head of the button and the base 15 of the pronged fastener. The body portion of the button is also inwardly crimped or swedged so as to form the inwardly extending ledge 19, although this ledge may be omitted in this 60 particular type of button if it be so desired, as the same function is performed by the filler 18. Thus when the button is to be used in connection with material which will 65 require considerable effort to force the

prongs of the fastener through the material, the filler will take up and transmit these stresses without danger of the collapsing or distortion of the body of the button.

The above-mentioned features may be applied with equal advantage to both the one and two-piece open top button, as disclosed in Figures 6, 7, 8 and 9, the one-piece open top button being disclosed in Figures 6 and 7, and the two-piece top in Figures 8 and 9. 75 The button illustrated in Figure 6 is formed with the one-piece open top head E and to which is permanently secured and anchored the pronged fastener B, the base 15 of the latter being rigidly held in place by the inwardly extending ledge 20 formed by the inward crimping or swedging of the body of the button as heretofore described. A disc 21 may be incorporated with this type of button, as illustrated in Figure 7, wherein 85 the base 15 of the fastener is provided with the disc extending thereabove, and the two being rigidly held and anchored in place by the inwardly extending ledge 22.

The button illustrated in Figure 8 is similar to that shown in Figure 6, with the exception that the head F of the button is formed in two pieces, being composed of the body portion 23 and the open cap 24 secured thereto. In like manner, the button disclosed in Figure 9 is similar to the button disclosed in Figure 7, with the exception that the head G is formed of two pieces, being composed of the body portion 25 and open cap 26 permanently secured thereto. 100

In some instances I have found it sufficient to form the hub of the button slightly smaller than the head of the fastener, as illustrated in Figure 10, so that the friction caused by forcing the head of the fastener 105 into the hub 27 is sufficient to hold the staple in place during the attachment of the button in place if the button is of the open top type, or until a filler 28 is assembled in the body of the button providing the button is of the 110 closed top type.

In some instances I have also found it desirable to provide the base 29 of the button as illustrated in Figure 11, with openings 30 already punched therein so as to prevent the 115 throwing down of a bur such as necessarily occurs when the prongs of the fastener are merely driven through the imperforate base of the button, as illustrated in the above-mentioned figures. These and similar 120 changes, however, it will be noted lie clearly within the scope of my invention. In the open top button the die with which the button machine engages the button, and drives the prongs of the fastener through the 125 material, is adapted to pass within the opening in the top of the button and contact either with the base of the fastener or with the blank which is situated directly thereabove, thus preventing any crushing or dis- 13

torting strains from being brought to bear upon the hub or body portion of the button and allowing this type of button to be used where considerable difficulty is experienced 5 in driving the prongs through the material to which the button is to be fastened. The permanent securement of the fastener and head also materially facilitates the handling of the button and simplifies the construction 10 of the entire button attaching machine.

Having thus described and explained my invention, I claim and desire to secure by Letters Patent:

15 A button of the class described comprising a body portion including a head, a hub and a base, the latter having independent perforations extending therethrough, a fas-

tener including a base and outwardly extending prongs, with the prongs extending through the independent perforations of the 20 base of the body portion, a disc approximating the size of and fitting within the hub and contacting with the base of the fastener, said hub provided with an inwardly extending ledge contacting with the disc and 25 securing the same and the fastener in place.

Signed at Waterbury in the county of New Haven and State of Conn., this ninth day of April, A. D. 1921.

FRANKLIN R. WHITE.
